WILLIAM F. PLANTIKO, OF STEVENS POINT, WISCONSIN

TOY VEHICLE

Application filed April 22, 1929. Serial No. 357,172.

This invention relates to new and useful improvements in toy vehicles.

- One of the objects of my invention is the provision of a toy vehicle incorporating in its construction a seesaw so as to provide a vehicle which will be especially useful for children whereby they will obtain a great deal of exercise in operating the vehicle as well as enjoyment in using the vehicle.
- Another object of the invention is the provision of a toy vehicle included in its construction a seesaw support for the children to ride upon, said support being eccentrically connected to the main axle of the vehicle so that when the vehicle is propelled over the surface, the supporting board will be rocked in the manner of a seesaw whereby the users of the vehicle will gain considerable exercise due to the movement of the supporting board upon which they are sitting, and also through the propelling of the vehicle over the surface.

A further object of the invention is the provision of a toy vehicle of the above type, wherein the supporting board thereof can be readily adjusted to accommodate children of different sizes, and the seesaw support is of such construction that it will readily accommodate one or two children at a time, and the action obtained from the movement of the support will be beneficial to the party thereon as it will be necessary for them to exercise their legs considerably for propelling the vehicle and also due to the movement of the supporting board upon movement of the vehicle.

With the above and other objects in view, the invention consists in the novel features of construction, the combination and arrangement of parts hereinafter more fully set forth, pointed out in the claims and shown in the accompanying drawings wherein:

Figure 1 is a side elevation of a toy vehicle constructed in accordance with my invention;

Figure 2 is a top plan view;

Figure 3 is a sectional view on the line 50 3—3 of Figure 1;

Figure 4 is a sectional view on the line 4—4 of Figure 1; and

Figure 5 is a sectional view on the line 5—5 of Figure 1.

In carrying out the construction of my improved toy vehicle, I provide a platform which comprises spaced boards 1 and 2. These boards 1 and 2 converge at one end and are connected by means of a U-shaped yoke 3. The lower ends of this yoke are disposed at right angles and secured to the ends of the boards 1 and 2. Before securing the ends of the yoke to the members 1 and 2, they are disposed at right angles to the body of the yoke as clearly illustrated in Figure 5. This positions the body of the yoke 3 at a point above the boards 1 and 2 to form a support for the front steering wheel 4.

The wheel 4 is mounted upon a transverse pin 5 and positioned between the arms of a yoke 6, attached to the lower end of a steering post 7. The post 7 is provided at its upper end with a handle 8 transversely of the post and in position to be readily grasped by the party using the vehicle.

The post 7 is disposed on an incline, as shown in Figure 1, and is arranged in this position by having the post pass through the ends of a pivotally mounted yoke 9. The yoke 9 has its intermediate portion disposed between the intermediate portion of the yoke 3 and a cross piece 10 carried by the yoke 3, and is retained in this position by means of a pin 11, having one end threaded to be engaged by a retaining nut 12.

From this, it will be apparent that the front end of the platform boards 1 and 2 are supported and the supporting wheel is used for steering the vehicle.

The ends of the boards 1 and 2 opposite the steering wheel 4 are slightly spaced and are supported by the axle 13. This axle is in turn supported by the traction wheels 14 on the ends thereof, while the intermediate portion of the axle is formed with a crank 15. Strap bearings 16' are used for connecting the axle 13 with the platform boards 1 and 2.

Connected up with the crank 15 and extending upwardly at an angle is a standard 16, the upper end of which is positioned be-

tween the arms of the U-shaped member 17 which in turn is connected to the tiltable platform or seat 18 by means of a bolt 19. The U-shaped member 17 has its arms provided 5 with a plurality of openings 20, any pair of which will be engaged by the bolt 21 for pivotally connecting the seat or platform 18 with the standard 16.

Supported upon the platform boards 1 and 10 2 are the inverted U-shaped standards 22, the intermediate portions being turned at right angles to the supporting legs and are each provided with a plurality of openings 23. The seat or platform 18 has bolted to the 15 underside thereto, by means of the bolts 24, a U-shaped member 25, the ends of which are formed with a plurality of openings 26, adapted to receive the securing bolts 27 which are used for connecting arms of the member 20 25 to the intermediate portions of the U-shaped standards 22.

It will be apparent that the bolts 27 may be passed through any one of the openings 26, aligned with any one of the openings 23 for 25 pivotally supporting, in conjunction with the U-shaped member 17, the seat or platform 18.

It will be apparent from the foregoing, that the seat or platform 18, through the adjustability of the U-shaped members 17 and 30 25 may be positioned at various angles and may also be raised and lowered in accordance with the size of the child using the vehicle.

The platform 18 may be adjusted so that 35 a smaller child may sit on the front end and do the steering, while a larger child may occupy the rear end and propel the vehicle which, during its movement will through the connection to the crank 15 of the platform 18 40 cause the platform to be operated in the manner of a seesaw whereby the child sitting on the rear of the platform will obtain considerable leg exercise through the up and down movement of the platform and the contact of 45 his feet with the surface over which the vehicle is traveling for propelling the vehicle forwardly.

It will be apparent that in the construction 50 of my improved toy vehicle, the parts are of a simple nature, so that they can be readily manufactured at a very low cost and the construction of the parts are also of such nature that it can be readily put together or taken apart and will occupy a minimum amount of 55 space for shipping purposes.

While I have shown and described the preferred embodiment of my invention, it will be apparent that slight changes may be made in the construction when putting the invention into practice without departing from the spirit of the same or the scope of the appended claim.

I claim:

A toy vehicle including a platform, a steering wheel supporting one end thereof, an axle

at the other end, traction wheels on the ends of the axle, a crank at the intermediate portion of the axle, spaced inverted U-shaped standards mounted on the platform and extending longitudinally thereof, a seat member, a U-shaped member having its intermediate portion secured to the underside of the seat member, means for adjustably connecting the ends of the U-shaped member to the intermediate portions of the standard, and means for adjustably connecting one end of the seat member with the crank of the axle.

In testimony that I claim the foregoing and have hereunto set my hand at Stevens Point, in the county of Portage and State of Wisconsin.

WILLIAM F. PLANTIKO.
